D. J. Mozart.

Watch.

N° 72528

Patented Dec. 24, 1867.

United States Patent Office.

DON J. MOZART, OF NEW YORK, N. Y.

Letters Patent No. 72,528, dated December 24, 1867.

IMPROVEMENT IN WATCHES.

The Schedule referred to in these Letters Patent and making part of the same.

TO ALL WHOM IT MAY CONCERN:

Be it known that I, DON J. MOZART, of the city, county, and State of New York, have invented new and useful Improvements in Watches; and I do hereby declare that the following is a full, clear, and exact description thereof, which will enable those skilled in the art to make and use the same, reference being had to the accompanying drawings, forming part of this specification.

The present invention relates to improvements in the escapement of watch and other time-movements, the principal object of which, and which is satisfactorily secured thereby, is to overcome and prevent any setting of the escapement, or, in other words, any setting of the escape-wheel. This result is accomplished by alternately giving an impulse to the balance-wheel or staff in the one direction, directly through such staff, and in the other direction by the passage of a tooth to the escape-wheel, over and by an eccentric-detent, which is properly connected therefor with the said balance-staff, through a trip or other equivalent device or devices; the said staff upon each and both of such impulses being independent of the "train," except when the impulses are received.

My improved escapement embraced herein, combines in itself the principle of both the "chronometer" and of the "lever" escapements, so called, and for this reason I have denominated it the "Chronometer-Lever Escapement," and in trade intend to so call it.

This escapement consists of a balance-wheel staff, cut out upon one side across its diameter, (wherein is embraced the principle of the "chronometer-escapement,") and of an eccentric-detent, (which, in principle, is similar to the "lever-escapement,") so formed and connected, through a trip or other suitable device or devices, with the said staff, that, when the escape-wheel, by one of its teeth, acting upon the cut-out portion of the balance-staff, has given an impulse to such staff, in the one direction, and has escaped therefrom, another tooth of the escape-wheel, in advance of the tooth which has just acted, is then passing into the said eccentric-detent, wherein, coming to a repose, by which no recoil on the train is occasioned, it so remains until, by the reaction of the coiled spring, such detent is swung or turned sufficiently for the tooth to the escape-wheel therein to pass over a surface thereof suitably jewelled to prevent wear, and through such surface to again impel the balance-wheel or staff, but, this time, in an opposite direction to that given to it through the direct impulse upon the staff. This tooth of the escape-wheel now escaping therefrom, the tooth following then comes to a repose upon the outside periphery of the detent, occasioning no "recoil" to the escape-wheel, until, by the reaction of the balance-spring, the cut-out portion of the balance-staff is brought into position for the tooth following the one which previously acted upon it to again similarly impel such staff, as well also as to swing the detent sufficiently for the tooth, at a repose upon its periphery, to enter the same, wherein, coming to a repose, and acting, as before, the balance-wheel is impelled in the opposite direction, and so on, as before.

Having thus, in general terms, stated the principles of the improved escapement embraced herein, I will now proceed to describe the same in detail, reference being had to the accompanying plate of drawings, in which—

Figure 1 is a plan view of the movement to a watch provided with my improved escapement.

Figure 2, a plan view, on an enlarged scale, of the escapement.

Figure 3, a section, taken in the plane of the line xz , fig. 2, and

Figures 4 and 5, detail views, to be hereinafter referred to, which views are taken in the planes of the lines yy and zz , respectively, of each other.

Similar letters of reference indicate corresponding parts.

A, in the drawings, represents the front plate to the frame carrying the watch-movement. To this plate A, upon its rear side, are fixed two bridges, B and C, the one, B, carrying the balance-wheel D, and the other, C, the main-spring barrel E, and train of gearing, F, between such barrel E, and the escape-wheel G, and the hand-arbor or spindle H. I, the balance-spring, connected and arranged with regard to the balance-wheel as in ordinary watch-movements. J, the staff to the balance-wheel D. This staff, upon one side, and across its width, in a line with its diameter, is cut out, as shown at K in the drawings, and upon the edge, L, of such cut-out portion, the teeth f , of the escape-wheel G, act in regular order and succession, as will be hereinafter described. M, a detent, hung by its spindle, N, to the plate A, between it and the outer end of the bridge C, in a position in advance of the staff to the balance-wheel. This detent is cut out at O, upon one side, across its width, so as to form two sides, P and Q, that, in direction, are such as to form an obtuse angle, R, with each other, with one of such sides Q, which is the one the farther removed from the balance-wheel staff when the indent is at rest, jewelled or otherwise suitably protected against wear by friction. The staff or spindle N to the detent M is cut out at S across its width, and in line with its diameter, and is inserted within the detent-eccentric to the centre of the same, and in such a position that the side surface T, to its cut-out portion, will coincide with the side P of the cut-out portion to the detent, but, with a bearing or surface, b, between it and

the inner end of the other side, Q, to the said detent, that, in direction, is on a circle from the centre to the detent-spindle. The detent, upon its upper end, by its collar or sleeve, U, surrounds the staff or spindle thereto, and over such sleeve is placed and secured one end of a trip-lever, V, that, by its other and outer end, through its notch, e, is engaged with the trip-pin d, secured in the projecting arm W, upon one side of a collet, X, secured to the balance-staff J. The trip-lever V, at its outer end, and upon each side from its notch, e, is provided with a similar side extension-piece or arm, Y, that, upon their outer edges e are curved or circular in shape, the radius of which curve is equal to or a little greater than that of the balance-staff at the point around which such arms play in the operation of the escapement to be hereinafter described. The collet X is partially cut away upon one side, under its projecting arm, to allow the trip-lever to properly operate.

The operation of the parts constructed and arranged as above described is as follows: By the revolution of the escape-wheel its teeth, in regular order and succession, abut against the edge to the cut-out balance-staff, and, in that manner, give a motion or impulse to the balance-wheel, in the direction represented by a red arrow in the drawings, fig. 2, when such tooth, escaping the balance-wheel, is then left free and independent of the train. But, as one tooth to the escape-wheel is thus acting upon the balance-staff, and is escaping therefrom, another tooth to such wheel, but in an advance position to the one acting on the staff, as stated, is entering the indent at its side, P, wherein, coming to a repose upon its interior circular bearing or surface, it there remains until, by the reaction of the balance-spring, acting through the trip-lever, the detent is turned sufficiently to allow the tooth within it to pass over, and by its jewelled surface, Q, whereon acting, the balance-staff is thereby impelled in the opposite direction, or that indicated by the black arrow in the drawings, fig. 2, when, such tooth escaping from the detent, the next tooth thereto, of the escape-wheel, comes to a repose upon the circular periphery of the detent. On this periphery the said tooth reposes until, by the reaction of the balance-spring, the balance-staff is brought into position for the tooth of the escape-wheel next to or following its tooth hereinabove described or referred to as having acted upon the balance-staff, to similarly act thereon; and thus to again impel the balance-wheel forward in the same direction as before, or as shown by a red arrow, and to again escape therefrom, at which time the tooth, referred to as at a repose upon the outside of the detent, then enters it, coming to a repose therein, as before described; the detent having been previously turned or swung sufficiently for such tooth to so enter, by the movement of the balance-wheel, acting through the lever-trip. Within the detent, the tooth, just above referred to as having entered the same, comes to a repose, and passes out therefrom, as before described, bringing the next tooth to a repose upon the outside of the detent, whereon reposing until, by the continued action of the escapement, another tooth acts upon the balance-staff, it also enters the detent, and so on, both with respect to the detent and the balance-staff, as long as the main-spring continues to act upon the escape-wheel through the movement-train.

By an escapement of the construction and arrangement of parts above described, as the repose for the escape-wheel is always on a circle, in the one instance upon the periphery of the detent, and in the other upon a circle, the centre of which is at the centre of the detent-spindle, it is plainly manifest that there no recoil is produced upon the escape-wheel, and that, in consequence thereof, there can be no setting of the escapement, or, in other words, of the escape-wheel—advantages and results of the utmost importance, as all conversant with watch and other time-movements are well aware.

In the above explanation of the construction and arrangement of the several parts to my improved escapement, I have described the trip-lever as provided with side projecting arms, each having its outer edge made of a curved circular shape. The object of giving this form to the lever-trip is to cause the trip to be self-banking, as it is operated through the trip-pin of the balance-staff, and, as is apparent, it is accomplished; for the moment the trip-pin leaves its notch, whether the balance is moving in either one or the other direction, as it then, by either one or the other of its curved arms, as the case may be, embraces the balance-staff, its further swings, either to the right or left, have ceased, and it must, of necessity, remain stationary until the trip-pin again moves it. By this construction of the lever-trip the ordinary banking-pins to the movement are dispensed with.

Among the many advantages secured by my improved escapement, embraced herein, in addition to that just above referred to as being secured by the self-banking lever-trip, may be here mentioned as the most important, and which, by a perusal of the description above contained, will be apparent to all conversant with watch-movements, first, that in the construction of the watch-movement, one wheel, one pinion, three jewels, at least, as well as many screws, are dispensed with, thus greatly reducing the expense of manufacture, as well in material as in labor; second, that with two-thirds, at least, less power than is now required with the ordinary escapement the movement may be run; and, third, that the bridge or frame-construction of the movement is greatly reduced in amount.

I claim as new, and desire to secure by Letters Patent—

1. An escapement, for watch or other time or other similar movements, in which are combined a cut-out staff and a cut-out eccentric-detent, or their respective equivalents, connected together through a trip-lever or other suitable device or devices, when both are constructed and arranged together for operation by the escape-wheel, substantially in the manner and for the purpose described.
2. A cut-out staff, a cut-out eccentric-detent, and a trip-lever, having one or more side arms, with its working-faces curved or circular in shape, or any equivalent therefor, respectively, in combination with the escape-wheel of a watch or other time or other similar movement, substantially as described, for the purpose set forth.

The above specification of my invention signed by me, this 2d day of July, 1867.

DON J. MOZART.
